UNITED STATES PATENT OFFICE.

MORRIS WISE, OF NEW YORK, N. Y.

HEEL FOR BOOTS AND SHOES.

SPECIFICATION forming part of Letters Patent No. 237,651, dated February 8, 1881.
Application filed December 31, 1880. (Model.)

To all whom it may concern:

Be it known that I, MORRIS WISE, a citizen of the United States, residing at New York, in the county of New York and State of New York, have invented new and useful Improvements in Heels for Boots and Shoes, of which the following is a specification.

This invention consists in a new article of manufacture—namely, a molded or pressed 10 boot or shoe heel consisting of a shell or casing formed from a single piece of material, with a solid bottom and continuous solid walls having outwardly-flaring edges, the interior of said shell or casing being filled with lifts of leather 15 permanently connected with each other and with the interior walls and bottom of said shell or casing, all of which will be more fully herein-after described.

In the accompanying drawings, illustrating 20 my invention, Figure 1 represents a perspective view of the improved heel constructed according to my invention. Fig. 2 is a longitudinal vertical section of the same. Fig. 3 is a plan view of the leather blank used to form 25 the heel-shaped shell or casing. Fig. 4 shows the male and female crimping-dies for making the heel-shaped shell or casing. Fig. 5 is a plan view of the female crimping-die. Fig. 6 is a like view of a female crimping-die having 30 a different outline from the one shown in the preceding figures. Fig. 7 shows the re-pressing or finishing die, in vertical section, placed opposite to the female crimping-die. Fig. 8 shows a re-pressing die used with a female 35 crimping-die corresponding to that shown in Fig. 5.

Similar letters indicate corresponding parts.

Referring to the drawings, the letter A indicates the shell or casing, which is brought by 40 the aid of suitable dies into the form of a heel of the contour or shape desired for the market, the said shell or casing being made from a single piece or blank of leather, with a solid bottom or tread and continuous solid walls, 45 all as a unit or integral, without any seam, the interior of said shell or casing being filled with lifts of leather for the purpose of imparting strength to the continuous walls of the shell or casing, thereby supporting the same against 50 lateral strain, and at the same time wearing

away with the walls and becoming the tread in case the bottom or tread of the shell or casing becomes worn away by usage. The continuous solid walls of the shell or casing flare outwardly at their upper edges and thereby form, 55 as it were, a flange or seat for enabling the heel, when filled with lifts, to be compactly seated and neatly adjusted upon the sole of the boot or shoe, and be connected therewith by sewing, nailing, or otherwise.

The lifts composing the core are cut into shape corresponding with the interior of the shell or casing, and are each coated with suitable cement, then stacked, connected together, and subjected to pressure, forming a solid core, 65 which is then coated with cement and inserted into the shell or casing, and again subjected to pressure in dies, thus finishing the heel ready for the market.

By constructing a heel for a boot or shoe according to my invention, as above described, a cheap, neat, and durable article is furnished to the market, ready for the manufacturer and completed for application to the sole of boots and shoes, there being present in the article 75 the continuous outwardly-projecting flange or seat above the core which enables the heel to be adjusted in position and connected with its sole.

If a shell or casing be made with the sole of 80 a boot or shoe to form a combined sole and heel therefor, as in English Patent No. 3,371, of 1865, as an article for the trade, it can only be attached to a boot or shoe provided with a double sole, as the upper must be stitched to 85 one of the soles, while the other serves as a foundation for sewing on the combined sole and heel; hence by such mode of connection the stitches are exposed along the edges of the sole. In the United States patent to Robert Taylor, dated February 29, 1876, is shown a machine for shaping the heels of boots and shoes; but in such machine the blank of leather is converted into a shell to form a heel without a bottom or tread, said bottom being 90 made by annexing a separate piece of leather or a lift to form the treading-surface. This differs from my invention, as I form the tread or bottom, together with the continuous solid walls, from a blank of leather, as an integral, 95 100

without a seam, the walls of the shell or casing having flaring edges for affording means to connect the heel with the sole.

In order to make a shell or casing for a boot or shoe and apply within the interior of the same a filling of lifts of leather, I select a piece or blank, A*, of leather, such as sole-leather, cut to the general form shown in Fig. 3, and soften it by immersing it in water for a period of about six hours. The blank in its softened condition is subjected to the action of dies C and D for the purpose of crimping and pressing the leather into the form of a shell or casing of the shape desired for the heel. Into the shell or casing thus crimped and pressed, while it remains in the female die C, are introduced the lifts, connected and coated with cement, as hereinbefore stated, which, as a core, is then subjected to the action of a re-pressing or finishing die, E, for a period of about ten minutes, whereby the core is firmly and permanently connected with the shell or casing and the heel completed ready for the market.

Prior to my invention a heel for boots and shoes has been made in form of a shell from a single piece of leather, said shell being afterward filled with leather or other material; but

in all such the filling which constitutes the core has not been made up of a series of lifts, each coated with cement, then stacked or piled one upon the other and connected together to form, as it were, a homogeneous body, which is then coated with cement and inserted into the shell, and all subjected to pressure for connecting the core with the interior of the shell, 35 as in my invention.

What I claim as my invention is—

The herein-described heel for boots and shoes, the same consisting of a shell or casing formed from a single piece of material, with the solid 40 bottom and continuous solid walls having outwardly-flaring edges, the interior of said shell or casing being filled with lifts of leather permanently connected with each other and with the interior walls and bottom of said shell or 45 casing, substantially as and for the purpose described.

In testimony whereof I have hereunto set my hand in the presence of two subscribing witnesses.

MORRIS WISE.
